US00D462525S

(12) **United States Design Patent** (10) Patent No.: **US D462,525 S**
 Grau et al. (45) Date of Patent: ** Sep. 10, 2002

(54) **TOOTHBRUSH**

(75) Inventors: **David George Grau**, Danville, CA (US); **Gary Lim**, San Francisco, CA (US); **Joseph Watson**, Naas (IE); **Mark Edward McConnell**, Foster City, CA (US); **Declan Connolly**, Clane (IE); **Niall O'Gara**, Salins (IE); **Robert Anthony Walsh**, Naas (IE); **Max Yoshimoto**, San Francisco, CA (US); **Jeff Hoefer**, San Jose, CA (US); **Dustin R. Brown**, Tempe, AZ (US)

(73) Assignee: **Gillette Canada Company**, Halifax (CA)

(**) Term: **14 Years**

(21) Appl. No.: **29/121,047**

(22) Filed: **Mar. 30, 2000**

(51) LOC (7) Cl. **04-02**

(52) U.S. Cl. **D4/104**
